ION GAUGE

Stanley Bashkin, Madison, Wis., assignor to the
United States of America as represented by the
United States Atomic Energy Commission

Application February 7, 1949, Serial No. 75,043

2 Claims. (Cl. 313—293)

1

The present invention relates to an improved ion gauge. Conventional ion gauges consist of an air-excluding jacket enclosing three concentrically arranged electrodes, the filament being the innermost electrode, the grid being a cylindrical electrode surrounding the filament electrode and the ion collector electrode being a cylindrical electrode surrounding the previous two. The filament electrode is electron emissive. It is surrounded by the positively charged grid electrode, and this in turn is surrounded by the ion collector electrode which is negatively charged with respect to the grid electrode and the filament electrode. In operation, electrons emitted from the electron emissive filament electrode are accelerated by the positive charge on the grid electrode and those which do not strike the grid electrode directly are caused to oscillate around the strands of which it is composed, until they are captured by the grid electrode or ions are formed when the electrons strike gas molecules. The ions formed by the rapidly moving electrons are, for the most part, positively charged ions.

One of the difficulties arising from the arrangement of electrodes in such previously known ion gauges is the trapping of positively charged ions in the volume defined within the grid electrode. Because of the relatively high potential on the grid electrode the positive ions, formed in the volume defined within said grid electrode, are repulsed from the grid electrode and a large number thereof are caused to strike the filament electrode to which they are attracted. This action results in two deleterious effects on the conventional ion gauge. One of these is the reduction in sensitivity which follows from the reduced number of positive ions reaching the ion collector plate. The second is the reduced life of the filament electrode resulting from the bombardment thereof by the positively charged ions enclosed within the volume defined by the grid electrode. The second effect is usually evidenced by the formation of a carbonaceous deposit on the filament electrode or of the wearing through and breaking of said electrode either of which necessitates frequent replacement thereof.

It is accordingly an object of the present invention to provide an ion gauge having a greater sensitivity than previously known ion gauges.

It is another object of the present invention to provide an ion gauge which retains its sensitivity over a longer period of time.

It is a further object of the present invention to provide an ion gauge which minimizes the bombardment of the filament and the formation thereon of a carbonaceous deposit.

2

It is a still further object of the present invention to provide an ion gauge having a longer filament life expectancy.

Other objects of the present invention will be in part obvious and in part pointed out hereinafter.

In one of its broader aspects, the objects of the present invention are achieved by providing an ion gauge which comprises, gas-excluding means adaptable to be connected with a vessel which may contain gas at very low pressure, an electrode assembly including a grid electrode, an ion collector electrode and a filament electrode within said means, said filament electrode being positioned between at least a portion of said grid electrode and at least a portion of said collector electrode so that charged particles passing from said filament to said portion of said collector electrode do not pass through a grid electrode, and means for measuring the current flowing to said collector electrode.

Two embodiments of the present invention are illustrated in the accompanying drawing and the manner of achievement of the objects of the present invention may be explained more clearly with reference to the drawing wherein:

Figure 1 is an elevation of a tube assembly with the jacket broken away along broken line 1—1 of Figure 2 and with a part of the collector electrode broken away.

Figure 2 is a horizontal section taken on the line 2—2 of Figure 1.

Figure 3 is an elevation of another tube assembly with the jacket broken away along broken line 3—3 of Figure 4 and with a part of its collector electrode broken away.

Figure 4 is a horizontal section taken on line 4—4 of Figure 3.

Referring to Figures 1 and 2, gas is excluded from an electrode assembly by a glass jacket 100. The jacket is preferably made of glasses such as those generally designated as Pyrex and Nonex. The jacket is essentially Pyrex glass with Nonex glass sealed thereto at the portions of the jacket 100 through which electrical contacts are sealed for connecting the electrode assembly with the tube exterior. The seal through the Nonex portions 90, 92, 94 and 96 was made by means of 10 mil tungsten wires 115, 117, 109 and 107. The chamber enclosed by the glass jacket 100 may be connected to a system which may contain gas at a very low pressure by means of the tapered ground glass joint 88. As in conventional ion gauges, electrons are emitted from a heated filament 106 which is supported on the nickel rods 113 and 111 which are in turn connected respec-

tively to the tungsten leads 117 and 115, said leads being sealed through the jacket 100 at the Nonex portions 90 and 92 respectively. The emitted electrons bombard the gas present within the jacket 100 and cause ionization of said gas. An ionic current therefore flows between the filament 106 and a collector plate 102 which collects the ions formed by the electrodes. The current intensity bears such a relation to the pressure of gas present in the jacket 100 that the pressure may be measured by measuring the current flowing to the collector plate 102. Electrical connection is made between the filament 106 and the collector plate 102 through an external current measuring device (not shown). The positioning of the collector plate 102 in the jacket 100 and the electrical connection to the jacket exterior is effected by the nickel rod 105 and the tungsten lead 107 which is sealed through the jacket 100 at the Nonex portion 96 thereof. In order to control and facilitate the emission of the electrons from the filament 106 a grid 104 is positioned within the volume defined by the generally cylindrically shaped collector plate 102 in relatively close proximity to the filament 106. Such a grid may be in the form of a conductive strand crimped in a zigzag configuration to define a generally rectangular shape.

As an example of the tube dimensions in one tube such as that illustrated in Figure 1, which tube was found to operate with higher efficiency than the conventional tubes, the following dimensions were found satisfactory. The electrodes were approximately 2 inches in height. The whole assembly was enclosed in a jacket of about 2 inches in diameter, the collector being spaced about $\frac{1}{8}$ of an inch from the jacket wall. The filament was spaced about $\frac{3}{8}$ of an inch from the jacket wall and the grid, which had a width of about $\frac{1}{2}$ of an inch, was spaced about $\frac{5}{8}$ of an inch from the same point on the jacket wall from which the filament was spaced $\frac{3}{8}$ of an inch. Electrical connection was made from the grid 104 to an external voltage control means (not shown) through the nickel rod 101 and the tungsten lead 109 which was sealed through the jacket 100 at the Nonex portion 94 thereof. A bent tungsten wire having a thickness of about 10 mil was found suitable for the filament 106 and the grid 104 and a nickel foil of approximately 5 mil in thickness, formed into a generally cylindrical shape, was found suitable as a collector plate 102. All metal to metal connections were made by spot welding. Conventional external electrical supply and detection means were used in conjunction with the tube.

Many alternatives of the electrode arrangement whereby at least a portion of the filament electrode is disposed between at least a portion of the collector electrode and a portion of the grid electrode such that electrons may pass between the portions of the filament and collector electrodes without passing through a grid will be apparent to one familiar with the art. One such arrangement is illustrated in Figures 3 and 4 wherein gas is excluded from an electrode assembly by a glass jacket 110 which may be connected to a system which may contain gas at very low pressure by means of the tapered ground glass joint 86. Electrons are emitted within said jacket 110 from a filament 118 and cause ions to form, which ions pass to either an inner collector plate 120 or an outer collector plate 114. The electrons emitted from the filament 118 are accelerated outwardly toward the collector plate

114 by causing a suitable high voltage to be placed on a grid 116 which is disposed between the filament 118 and the outer collector plate 114. Such a grid may have, for example, a helical shape. Electrical connection to the tube exterior from the grid 116, the filament 118 and the collector plate 120 and 114 is made by means of the nickel rods 130, 132 and 134 respectively and the tungsten leads 136, 138 and 140 respectively, said leads being sealed through the Nonex portions 142, 144 and 146 of the jacket 110. Conventional electrical supply and measuring apparatus (not shown) is employed in the external circuit.

The following is offered as an explanation of the more efficient operation of ion gauges provided by the present invention over those provided by prior ion gauges although it will be understood that the concept of the present invention is not limited by the accuracy of this explanation. Referring to Figure 2, electrons are emitted from filament 106. Those electrons which are emitted toward the portion of the ion collector 102 on the filament side of broken line A-A will be repulsed by the low potential on the ion collector 102 toward the grid 104. The high potential on the grid 104 will attract the electrons repulsed from the aforementioned portion of the ion collector 102 past the filament 106 and some of those electrons which do not strike the grid 104 will oscillate around the strands thereof until they have struck a molecule and formed an ion, or until they strike the grid 104. Some of the electrons emitted from filament 106 toward the grid side of the collector plate 102 will proceed directly toward the grid 104, and will spiral around said grid 104 as hereinabove described. Whatever positive ions are formed along any of these electrons paths will be in such a position with respect to the ion collector plate 102 that they will not have to pass through the grid 104 to reach said collector plate 102 and thus substantially all positive ions formed will be collected on collector plate 102.

A similar phenomenon occurs in the apparatus illustrated in Figures 3 and 4. Positive ions formed between the filament 113 and the collector 120 will be attracted to the collector 120 since the collector potential is below that of the filament potential. Similarly, ions formed between the grid electrode 116 and the filament electrode 118 will, for the most part, be attracted past the higher potential filament 118 to the lower potential collector 120. Those ions formed between the grid 116 and the outer collector 114 will be collected without any interference on the outer collector 114.

The materials and potentials which may be used in the present invention are substantially the same as those used in a conventional ion gauge. For example, the grid potential may be kept at about 100 volts above the filament potential and the collector may be kept at a potential approximately 20 volts below the filament potential. The substitution of other materials for the nickel and tungsten employed in the disclosed embodiments is not a departure from the scope of the present invention. It is desirable to keep the volume of the ion gauge relatively small, thus, for example, the space between the collector electrode and the envelope serves no useful purpose and should be minimized.

Gauges within the scope of the present invention such as those described above have been found to operate with higher efficiency and with greater sensitivity than previously known gauges.

The useful life of the filament is greatly extended and relatively small deposits of carbonaceous material form within comparable time to that in which filaments of previously known ion gauges were coated so as to materially reduce the efficiency of the gauge. In addition, the filament of such a gauge was not worn away after continued use to the extent that could be expected for previously used gauges.

It is apparent from the foregoing that the present invention provides a very highly efficient gauge. It will be understood that the scope of the present invention is not limited to the two illustrative embodiments set forth and represented in the figures but that other variations may be employed without departing from the substance of the present concept. Thus, for example, filaments might be disposed on both sides of the grid 104 rather than on the one side only as indicated by the broken line 105 in Figure 2. Similarly, a filament and grid and collector plate might be incorporated in that order outside the collector plate of either of the illustrative embodiments set forth thus making a series of collector, filament, grid, collector, filament, etc. Other variations which provide free access of ions formed in the ion gauge to the collector plate will be apparent to those familiar with the art.

Since many embodiments might be made in the above-described invention and since many changes might be made in the embodiment illustratively disclosed herein, it is to be understood that all matter hereinabove set forth is to be interpreted as illustrative only and not in a limiting sense.

I claim:

1. A detector tube for an ionization gauge which comprises gas-excluding means adapted to be connected with a vessel which contains gas at very low pressure, said means enveloping a grid electrode consisting of a conductive strand crimped in zigzag configuration to define a generally rectangular shape; a cylindrical ion collector electrode and a conductive strand filament electrode positioned in separative relation between at least a portion of said grid electrode and at least a portion of said collector electrode.
- 10 2. A detector tube for an ionization gauge which comprises gas-excluding means adapted to be connected with a vessel which contains gas at very low pressure, said means having a generally cylindrical shape and enveloping a collector electrode which closely conforms to the shape of the cylindrical portion of said means, a grid electrode consisting of a conductive strand crimped in a zigzag configuration to define a generally rectangular shape, a filament electrode consisting of a conductive strand crimped to form an inverted V, said grid electrode and filament electrode being juxtaposed in and enveloped by said cylindrical collector electrode.
